UNITED STATES PATENT OFFICE.

WALTER M. MITCHELL, OF EVANSTON, ILLINOIS.

DESIGN FOR A DISPLAY-STAND.

SPECIFICATION forming part of Design No. 26,322, dated November 24, 1896.

Application filed September 26, 1896. Serial No. 607,117. Term of patent 7 years.

To all whom it may concern:

Be it known that I, WALTER M. MITCHELL, of Evanston, in the county of Cook and State of Illinois, have invented and produced a new and original Design in Display-Stands, of which the following is a specification.

The display-stand of my design is particularly useful in supporting goods, such as bolts of cloth, dress-goods, books, &c., in display-windows, and is shown in the accompanying drawings, in which—

Figure 1 is a perspective view of the display-stand in position to support a bolt of cloth or other goods in a vertical position; and Fig. 2 is a perspective view of the display-stand as it would be placed to act as a prop or oblique support for boxes, &c.

The leading feature of my design consists in a display stand or support for goods, con-

structed of a single piece of wire bent into an irregular form with its meeting ends abutted and secured together wherein three loops of the wire provide a base from which an upright loop of wire extends perpendicularly, and when the perpendicular member is caused to form one of the base-supports a tripod is produced with an obliquely-projecting member.

In the drawings, A B C D represent the loops of the wire, and E a collar inclosing the abutting ends thereof.

30

I claim—

The design for a display-stand or goods-support, substantially as herein shown and described.

WALTER M. MITCHELL.
